UNITED STATES PATENT OFFICE.

CONSTANTIN RIEGGER, OF NEW YORK, N. Y.

TANK-BALL.

1,334,793.

Specification of Letters Patent. Patented Mar. 23, 1920.

Application filed December 12, 1913. Serial No. 806,247.

To all whom it may concern:

Be it known that I, CONSTANTIN RIEGGER, a citizen of the United States, and a resident of the city of New York, borough of Manhattan, county and State of New York, have invented a new and improved Tank-Ball, of which the following is a full, clear, and exact description.

This invention relates to improvements in tank balls, and has for an object to provide an improved structure wherein the ball is prevented from collapsing during the seating and during the unseating thereof.

Another object of the invention is to provide a ball with a reinforcement in the interior of the upper part.

A further object of the invention is to provide a tank ball with a reinforcement in the upper part, and a reinforcing member at the edge co-acting with the reinforcement in the top for making a good joint therebetween.

A still further object of the invention is to provide a ball with a hemispherical bottom and a conical top, the top being reinforced so that the same and the upper edges of the bottom will be properly braced against the usual collapsing tendency.

Another object of the invention is to provide a reinforcement at the seam so as to prevent the opening thereof.

In carrying out the object of the invention a hemispherical or substantially hemispherical bottom portion is provided which is formed of flexible material so as to properly accommodate itself to the seat. Associated with this hemispherical bottom is a top which may be substantially hemispherical or may be conical, and which is provided with a reinforcement, preferably arranged on the interior. The reinforcement extends to the point of juncture between the top and bottom. Preferably an annular inwardly projecting flange is arranged at the point of juncture between the upper and lower part of the ball so as to strengthen said point and act as a bracing member. This flange may be made independent or may be caused to partially inclose the bottom edge of the reinforcement of the conical shaped upper portion of the ball so as to provide a good joint between the reinforcement and the upper part of the ball and the juncture between the upper and lower portion of the ball.

In the accompanying drawing—

Figure 1 is a side view of an embodiment of the invention;

Fig. 2 is a longitudinal vertical section through the structure shown in Fig. 1; 60

Fig. 3 is a side view of a slightly modified form of the invention to that shown in Fig. 1;

Fig. 4 is a longitudinal vertical section through the structure shown in Fig. 3; 65

Fig. 5 is a fragmentary view showing a structure similar to the structure shown in Fig. 4 but showing the annular flange or reinforcement extending below or beyond the line of juncture of the upper and lower 70 part of the ball;

Fig. 6 is a view similar to Fig. 5 except that the upper reinforcement is omitted and only an annular reinforcing ring is shown.

Fig. 7 is a view similar to Fig. 6 except 75 that the reinforcement is directly at the seam or line of weakness, and is vulcanized so as to be integral with the upper and lower portions of the ball.

Referring to the accompanying drawing 80 by numeral 1 indicates the usual rod designed to be connected with the spud 2 associated with the upper part of the ball 3. The ball 3 is substantially a sphere, the bottom 4 being formed of rubber more or less 85 soft in the usual manner so as to allow the same to be properly seated. The upper part 5 is also made of rubber more or less soft, but in order to prevent the same from collapsing a reinforcing and stiffening member 90 6 is provided, which may be made of any desired material, as for instance, rubber, either of a good quality or a poor quality, provided the same is comparatively stiff. The lower edge of the reinforcement 6 is 95 provided with an enlargement 7, whereby the center of the ball 3 is stiffened, which affects the lower part of the ball or bottom portion 4 so as to hold the same against elongating. It will also be observed that a 100 bead 8 is provided at the equator of the ball. Arranged interiorly of ball 3 is a circumferential flange 9 bent over the enlargement 7 and preferably vulcanized thereto, whereby a good strong joint is provided. 105

Figs. 3 and 4 disclose the same general principle as shown in Figs. 1 and 2, but the top 5' is formed conical, while the bottom 4' is hemispherical, similar to the form of the invention shown in Figs. 1 and 2. The 11

reinforcement 6' (Fig. 4) acts in a similar manner to reinforcement 6 shown in Fig. 2, but is of course formed conical so as to conform to the conical upper portion 5'. It will be noted that the bottom 4' is made continuous with top 5, and with a line 10 indicating where the upper and lower parts of the ball join.

In Figs. 5 and 6 modified forms of the invention to that shown in Fig. 4 are disclosed. For instance, in Fig. 5, the bottom 4' and the top 5' are provided with the usual line or point of juncture 10, but the annular flange 9 is omitted. However, the reinforcement 6' extends downwardly to a point 11 which is below the line of juncture, or line of weakness 10, whereby said line of weakness is reinforced and braced. As considerable strain comes at this point the enlargement 7 is provided, which provides an ample bracing member which is non-collapsible, but which is preferably made from a hard rubber or gum, and therefore is slightly yielding under heavy pressure. In Fig. 6 the same form of ball is shown to that disclosed in Fig. 5, but there is provided no reinforcement for the conical part of the ball which may be made flexible or comparatively stiff, as desired. However, an annular reinforcing or stiffening member 12 is provided which extends an appreciable distance on each side of the line of juncture or weakness 10 so as to brace both the upper part of the ball and the lower part.

In constructing a tank ball with the reinforcements it is designed to provide means which will positively prevent the objectionable elongation of the ball during the flushing operation, or thereafter. Also, the reinforcement provided will prevent the elongation of the ball when lifting the same from its seat. This is especially true in regard to the conical shaped top 5' shown in Figs. 3 and 4 as this form of the invention allows the ball to easily rise through the water.

In Fig. 7 another slightly modified form is shown in which the upper portion 5' and the lower portion 6' are vulcanized together in the usual manner, but is provided at the juncture with a reinforcement 13 which is vulcanized so as to be integral with the upper portion and the lower portion, and preferably to straddle the seam or line of weakness 10.

The use of the term "rubber" or "rubber composition" is intended to cover the ordinary commercial rubber and the various compositions made therefrom together with any suitable material performing the same functions.

What I claim is—

1. A tank ball formed with a seat engaging portion of flexible rubber, an upper portion of flexible rubber, and a reinforce-

ment formed of rubber composition vulcanized to the upper portion for preventing the collapsing thereof, said reinforcement being formed with an annular enlargement opposite the juncture of the seat engaging portion and the upper portion. 70

2. A tank ball formed with a seat engaging portion, an upper portion, a reinforcement at the juncture of the seat engaging portion and upper portion for preventing 75 undie collapsing of the seat engaging portion, and means associated with said reinforcement and vulcanized to said upper portion for preventing the collapsing of the upper portion.

3. A rubber tank ball formed with a seat portion, an upper flexible portion, a separate stiffening member of hard rubber arranged interiorly of said flexible upper portion to prevent the collapsing thereof, and 80 also to prevent the collapsing of the upper edge of the seat portion; and a reinforcing member of rubber arranged at the juncture of the upper portion and the lower portion, said reinforcing member of rubber overlapping said stiffening member for providing a substantially rigid joint. 90

4. A float ball valve having a bulb formed with a seat engaging portion and an upper portion, a stiffening member conforming 95 with and secured to the inner wall of said upper portion, and a reinforcing member secured to the interior wall of the bulb at the junction of the seat portion and upper portion and embracing the rim of said stiffening member. 100

5. A float ball valve formed with a flexible seat engaging portion, a top portion, a stiffening member interiorly arranged at the joint or seam between the top portion 105 and the seat engaging portion to prevent the collapsing and the opening of said seam, and a reinforcing member overlapping said stiffening member for providing a substantially rigid joint. 110

6. A float ball valve formed with a flexible seat portion, an upper portion, a separate stiffening member arranged interiorly of said upper portion to prevent the collapsing thereof, and also to prevent the collapsing of the upper edge of the seat portion, and a reinforcing member arranged at the juncture of the upper portion and the lower portion, said reinforcing member overlapping said stiffening member for providing a substantially rigid joint. 115

7. A bulb for tank valves, comprising an upper portion having a core of relatively hard vulcanized rubber and an outer covering of relatively soft rubber secured to said core throughout its entire upper surface, and a lower portion of soft rubber secured to the edges of said outer covering and the inner margin of said core. 125

8. A bulb for tank valves, comprising an 130

upper portion having a supporting shell of relatively hard material, a covering of relatively soft rubber extending around the inner and outer margins of said shell, and a 5 lower portion of soft rubber secured to said rubber.

9. A bulb for tank valves, comprising an upper portion having a core of relatively hard material and an outer covering of relatively soft rubber secured to said core throughout its entire upper surface and extending around its inner margin, and a lower portion of soft rubber secured to said outer and marginal coverings. 10

15 10. A bulb for tank valves, comprising a

continuous outer layer of relatively soft rubber, a support for the upper portion thereof comprising a core of relatively hard material shaped to conform to said upper portion, said soft rubber having an internal 20 projection extending around the inner margin of said core.

In testimony whereof I have signed my name to this specification in the presence of two subscribing witnesses:

CONSTANTIN RIEGGER.
